ADVERTISING AND DISPLAY DEVICE

Harry R. Stern, New York, N. Y.

Application February 18, 1933, Serial No. 657,369

8 Claims. (Cl. 40—33)

The present invention relates to advertising and display devices and is more particularly directed toward devices for the displaying and advertising of comparatively small objects such as 5 watches.

The present invention contemplates a device for displaying small objects carried on a rotating shaft and associated with an illuminating device and a stroboscopic disc, so that one can 10 view the device as though it were stationary.

A further object of the invention is to provide an arrangement whereby there is a continuous 15 slip between these rotating parts, so that one obtains different aspects of the article under display as the disc moves relative to the article being displayed. If the disc is caused to slip slightly 20 on the shaft driving the displayed article, the eye will see the article slowly revolving on the shaft and will, therefore, be able to see all sides 25 of the article.

Other and further objects of the invention will appear as the description proceeds.

The accompanying drawings show, for purposes of illustrating the present invention, two of the 25 many embodiments in which the invention may take form, it being understood that the drawings are illustrative of the invention rather than limiting the same. In these drawings:

Fig. 1 is a vertical sectional view through a 30 form of device adapted for displaying a watch;

Fig. 2 is a sectional view on the line 2—2 of Fig. 1;

Fig. 3 is a perspective view of the device shown in Fig. 1;

Figs. 4 and 5 are detached views showing different forms of disc;

Figs. 6A—6E, inclusive, are diagrammatic illustrations to show how the watch appears as it passes through one-half of the cycle;

Fig. 7 is a horizontal sectional view through a modified form of construction; and

Figs. 8 and 8a illustrate two aspects of a different form of article which may be displayed.

The device is preferably made up for use in a 45 show window or other public place and in order that the article being displayed may be easily observed during the day time, or when the show window is lighted, the device is designed to cut out extraneous light.

As shown in the drawings, it has a lower compartment 10 for the operating mechanism and an upper compartment 11 adapted to contain the article being displayed, for example a watch W as indicated by the drawings. The separation between the two compartments is formed by a parti-

tion or diaphragm 12 having an aperture indicated at 13. A driving motor 14, such as a small electric motor, is suitably mounted in the lower chamber and is connected to a suitable driving mechanism such as the disc 15 carried by a vertical 60 shaft 16. This shaft is mounted in bearings 17 and 18, or in any other desired manner. The upper end of the shaft is adapted to receive a coupling device 19 secured to the watch W or other article. The shaft 16 also carries a stroboscopic 65 disc 20 having a slot 21 somewhat smaller than the opening 13 in the partition 12. A light source such as an ordinary incandescent lamp is shown at 22.

The disc 20 may be permanently secured to the 70 shaft 16, but for certain types of display the disc should be secured to the shaft to permit relative rotation between the parts. A convenient method of securing is to employ spring washers 24 and an adjusting ring or nut 25 threaded on to the 75 shaft 16.

The disc 20 is here shown as provided with fan blades 26, 27 which afford considerable resistance to the rotation of the disc and this resistance may be made sufficient to make the disc slip slightly 80 on the shaft 16, causing the disc to make a few less revolutions per minute than the shaft. The blades 26 provide for a quick cut-off of the light.

In operating the device the shaft 16 is driven at a speed of sixteen or more revolutions per second, so that there is persistence of vision with 85 respect to the article being displayed when illuminated by light passing through the slot 21.

When the slot 21 is in line with the face of the watch, and the friction discs are clamped sufficiently tight to prevent slippage of the disc 20 on the shaft, one sees the face of the watch as 90 though it were stationary. This is indicated at A in Fig. 6a. The heavy backlines indicate the dark background around the watch. If, however, 95 the disc is allowed to slip slightly, one will obtain a continuously changing view of the watch. The watch will appear to revolve in the direction of its real direction of rotation. A few of these 100 succession of views are indicated at B, C, D, and E of Figs. 6B—6E, inclusive. In view B one sees the face of the watch turned more or less on edge; in view C the watch is entirely on edge; in view D the watch is on edge but the back view of the watch is seen instead of the face; and in view E 105 the full back view of the watch is seen together with any advertising matter or other design which may be carried on the back of the watch. Owing to the rotation of the watch and the stray light which will be picked up by it, there may be a 110

slight blur of circular shape. This is indicated by the lighter lines in the background of views B, C, and D.

The watch can run while being rotated and hence a continuously changing appearance is given as time passes, demonstrating the durability and reliability of the watch.

The disc shown in Fig. 5 is the same as that shown in Fig. 4, except that a small hole 28 is provided opposite the hole 21. This will give two views of the watch, one a strongly illuminated face view and the other a phantom-like, dimly illuminated, rear view of the watch. It is obvious that the slippage of a disc such as shown in Fig. 15 will cause these views to interchange.

While the drawings show slippage of the disc relative to the shaft, it is, of course, obvious that slippage could be had between the shaft and article to be displayed.

20 In the form shown in Fig. 7, the disc 20' is provided with one opening 31, while the portion 37 has three openings 34, 35, and 36. The watch W is carried in the same position as before. The openings 35 and 36 may carry differently coloured sheets of gelatin 32 and 33, or other transparencies. The openings 31 and 34 are clear. When the watch and stroboscopic disc of the nature just referred to are revolved, one obtains a strongly illuminated watch face in the plane indicated in 25 the full lines of the drawings, and two dimly illuminated or colored watch faces in the dot and dash, and dotted line positions.

30 Figs. 8 and 8a illustrate the display of a different form of article, such for example as a piece of unwrapped candy, indicated at 40, and a piece of wrapped candy, indicated at 41. The two pieces of candy are placed on opposite sides of a support and revolve in the same way as the watch above described.

40 From the foregoing it will be apparent that the present invention affords a convenient advertising device for displaying small articles and provides an arrangement for revolving and illuminating the article, either so that one side only 45 may be viewed, or so that both sides may be seen in quick succession.

It is obvious that the invention may be embodied in many forms and constructions within the scope of the claims, and I wish it to be understood that the particular forms shown are but 50 two of the many forms. Various modifications and changes being possible, I do not otherwise limit myself in any way with respect thereto.

What is claimed is:

55 1. An advertising device comprising a rotary shaft, a stroboscopic disc carried by the shaft, a light source adjacent one side of the disc and adapted to project a beam of light through the opening in the disc, an article to be displayed secured to the shaft for rotation therewith and placed in the path of the beam of light, and an enclosure for the disc and light source, the enclosure having an aperture for the light beam, the article being outside the enclosure.

65

70

75

2. An advertising device as claimed in claim 1, wherein one of the shaft rotated articles is connected to the shaft through a friction drive adapted to permit the same to slip so as to turn at a slightly slower speed than the other article whereby different areas of the article to be displayed are illuminated in succession so that the displayed article appears to slowly rotate.

3. An advertising device as claimed in claim 1, wherein the disc is frictionally mounted on the shaft so as to slip behind the shaft whereby the view of the article progresses.

4. An advertising device as claimed in claim 1, wherein the disc is provided with depending light screens adjacent the opening to confine the light beam.

5. An advertising device as claimed in claim 1, having an enclosing hood about the article being displayed to cut off extraneous light.

6. An advertising device comprising a vertical shaft, an article to be displayed secured to the upper end of the shaft, a motor drive for the shaft adapted to rotate the shaft at a speed above the persistence of vision, a stroboscopic disc carried by the shaft, a lamp bulb underneath the disc and adapted to project a beam of light through the opening in the disc toward the article to be displayed, and an enclosure for the disc, lamp and lower part of the shaft, the upper wall of the enclosure having a light transmitting opening between the lamp bulb and the article to be displayed.

7. An advertising device comprising a vertical shaft, an article to be displayed secured to the upper end of the shaft, a motor drive for the shaft adapted to rotate the shaft at a speed above the persistence of vision, a stroboscopic disc frictionally carried by the shaft, means for imposing a drag on the disc to cause it to slip relative to the shaft, a lamp bulb underneath the disc and adapted to project a beam of light through the opening in the disc toward the article to be displayed, and an enclosure for the disc, lamp and lower part of the shaft, the upper wall of the enclosure having a light transmitting opening between the lamp bulb and the article to be displayed.

8. An advertising device comprising a vertical shaft, an article to be displayed secured to the upper end of the shaft, a motor drive for the shaft adapted to rotate the shaft at a speed above the persistence of vision, a stroboscopic disc frictionally carried by the shaft, the disc having a fan blade to stir the air and cause resistance whereby the disc slips relative to the shaft, a lamp bulb underneath the disc and adapted to project a beam of light through the opening in the disc toward the article to be displayed, and an enclosure for the disc, lamp and lower part of the shaft, the upper wall of the enclosure having a light transmitting opening between the lamp bulb and the article to be displayed.
